UNITED STATES PATENT OFFICE.

MAGDALENA MARQUA, OF CINCINNATI, OHIO, ASSIGNOR OF ONE-HALF TO
GEORGE W. HARDING, OF CINCINNATI, OHIO.

SCRUB-BRUSH.

SPECIFICATION forming part of Letters Patent No. 711,777, dated October 21, 1902.

Application filed February 15, 1902. Serial No. 94,234. (No model.)

To all whom it may concern:

Be it known that I, MAGDALENA MARQUA, a citizen of the United States of America, and a resident of Cincinnati, in the county of 5 Hamilton and State of Ohio, have invented certain new and useful Improvements in Scrub-Brushes, of which the following is a specification.

This invention relates to certain improvements in brushes, and more especially in that class of brushes which are designed for use in washing or scrubbing; and the object of the invention is to provide a brush of this general class of a simple and inexpensive nature and of a strong and durable construction having simple and improved means for preventing splashing or splattering of the soapy water or suds on surrounding objects or the person when the brush is in use, said means 15 also serving in properly dipping or bailing the water from a bucket or the like, so that the use of a cloth for this purpose is obviated.

The invention consists in certain novel features of the construction and combination 25 and arrangement of the several parts of the improved brush whereby certain important advantages are attained and the device is made comparatively simple and cheap and is otherwise adapted and made convenient and 30 efficient for use, all as will be hereinafter fully set forth.

The novel features of the invention will be carefully defined in the claims.

In the accompanying drawings, which serve 35 to illustrate my invention, Figure 1 is a side elevation showing a brush constructed according to my invention. Fig. 2 is a face view showing the bristle side of the said brush. Fig. 3 is a cross-section taken transversely 40 through the improved brush; and Fig. 4 is a sectional view similar to Fig. 3, but showing a modified construction of the improved brush.

Referring first to Figs. 1, 2, and 3, 1 indicates the back or stock of the improved brush, 45 usually formed from wood and carrying on its under surface bristles 2 in a well-known way. The structure of the brush-back and the means for holding the bristles thereon form no part of my present invention and 50 may be varied as desired without departure from my invention. As herein shown, the

brush has pointed ends 3, serving to permit of inserting the brush in corners and crevices; but it is evident that the ends may also be straight. Along the edges of the 55 brush-back 1 are secured pendent portions of flexible material, preferably formed from sheet-rubber or equivalent flexible and sufficiently elastic material, and these pendent portions form a skirt encircling the brush and 60 extending down almost to the lower edge thereof, the lower ends of the bristles 2 only being left uncovered, as shown in Figs. 1 and 3. These pendent portions comprise elongated side portions 4 4, formed from elongated 65 strips of sheet-rubber, and end portions 5 5, formed from shorter strips of sheet-rubber, and both the side and end portions 4 4 and 5 5 are held to the brush-back 1 by means of nails or tacks 6, passed through their upper edges 70 and driven into the edges of the said back. The ends of the side portions 4 4 are lapped over outside of the corresponding ends of the end portions 5 5, as shown at 7 in the drawings, and the nails or tacks 6 at these points 75 are driven through both plies or thicknesses of the sheet-rubber into the edges of the brush-back 1. By this means it will be seen that the side portions and end portions 4 4 and 5 5, respectively, form a continuous skirt extended 80 around the sides and ends of the brush and pendent below the brush-stock 1 almost to the lower ends of the bristles, and this continuous skirt serves when the brush is in use to prevent splashing or spluttering of the water 85 or suds about, especially on the wall decorations or hangings to deface them or on the person, and effectually holds the water under the brush, where it will be of service in removing the dirt or stains and preventing 90 it from spreading about over the floor, wood-work, or elsewhere in use. The pendent skirt being extended around the entire edge of the improved brush also serves as a means for dipping or bailing water from a bucket or 95 the like and applying such water to the spot where it is desired to wash or scrub, this being accomplished by merely inverting the brush when placed in the bucket, so that the space inclosed within said skirt upon the under side of the brush may be supplied or filled 100 with water.

In the modified form, Fig. 4, I have shown a reinforcing thickness or beading 8 along the upper edge of the skirt, under which the attaching-nails 6 are inserted. This beading 5 serves as a guard to prevent the nail-heads coming in contact with the woodwork or person and provides against undue wear and consequent disengagement or parting of the skirt from the back by tearing away or the 10 like.

The skirt being formed of sheet-rubber or other suitable yielding and sufficiently elastic material also serves to brace or strengthen the tufted bristles and prevents them from 15 being broken down by pressure on the brush in scrubbing, and since the said skirt is preferably formed in parts or sections 4 4 and 5 5, lapped at their adjacent ends, it is evident that there is no liability of tearing the sheet 20 material during the use of the brush, since the lapped ends of the several parts or sections will move upon each other to permit the required spreading of the bristles when the brush is pressed upon the floor, woodwork, or 25 elsewhere in use. It will also be seen that since the skirt is extended continuously around the sides and ends of the brush it affords a better hold for the hand thereon and its lower edges afford protection, to a certain extent, for the 30 fingers and prevent injury thereto from splinters and the like. Also the said skirt permits of being partially filled with water when in inverted position, so that soap may be rubbed on the brush-surface while the water is held there- 35 in by the skirt, and there is no necessity for afterward frequent dipping of the brush in the water bucket or pail. By this means a very considerable economy in the use of soap is effected, since after the soap is applied to the brush it is not washed off and lost in the water contained in the pail, but may be at once applied to the floor, wood-work, or other surface for use. The skirt also adds materially to the stiffness of the 40 bristles, so that the wear is upon the points of the bristles instead of upon their sides, (as is the case in ordinary brushes,) and in this way the life of the brush is considerably 45 lengthened. It will also be obvious from 50 the above description of my improvements

that the brush is capable of considerable modification, and they may be easily applied to street and other brooms without material departure from the principles and spirit of the invention, and for this reason I do not 55 wish to be understood as limiting myself to the precise form and arrangement of the several parts herein set forth.

Having thus described my invention, I 60 claim—

1. A brush comprising a back provided with bristles on its under surface and a skirt of flexible sheet material extended continuously around its sides and ends, the said skirt being secured at its upper part to the side and 65 end edges of the brush-back, and having its lower part pendent below said back outside of and around the said bristles and forming within it a space for holding water when the brush is inverted and said skirt preventing 70 splashing of the water when the brush is in use, substantially as set forth.

2. A brush comprising a back provided with bristles upon its under surface and a skirt of flexible sheet material extended continuously 75 around its sides and ends, the said skirt being secured at its upper part to the side and end edges of the brush-back and having its lower part pendent below said back outside of and around the said bristles and forming 80 within it a space for holding water when the brush is in inverted position and said skirt preventing splashing of the water and being formed of a plurality of parts or sections the end portions of which are lapped upon each 85 other and secured to the edges of the back, substantially as set forth.

3. A brush comprising a back provided with bristles upon its under surface and having a pendent skirt of flexible sheet material extended continuously around its sides and ends, the said skirt having a beading or reinforcing-guard around and along its upper edge, substantially as set forth.

Signed at Cincinnati, Ohio, this 11th day 95 of February, 1902.

MAGDALENA MARQUA.
